UNITED STATES PATENT OFFICE

104,045

DESIGN FOR A CHAIR SEAT COVERING

John Perona and Joseph Perona, New York, N. Y.

Application December 19, 1936, Serial No. 66,663

Term of patent 7 years

To all whom it may concern:

Be it known that we, John Perona and Joseph Perona, citizens of the United States of America, residing at New York city, New York, have invented a new, original, and ornamental Design for Chair Seat Covering, of which the following is a specification, reference being had to the accompanying drawing, forming part thereof.

The figure is a plan view showing the new chair seat covering.

We claim:

The ornamental design for chair seat covering as shown.

JOHN PERONA.
JOSEPH PERONA.
